UNITED STATES PATENT OFFICE.

WALTER V. TURNER, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

SELECTING-VALVE DEVICE.

1,162,825.

Specification of Letters Patent.

Patented Dec. 7, 1915.

Application filed March 1, 1913. Serial No. 751,396.

To all whom it may concern:

Be it known that I, WALTER V. TURNER, a citizen of the United States, residing at Edgewood, in the county of Allegheny and State of Pennsylvania, have invented new and useful Improvements in Selecting-Valve Devices, of which the following is a specification.

This invention relates to steam driven locomotives, and more particularly to those in which a steam superheater is employed.

Where a locomotive is equipped with a steam superheater, it is sometimes the case, such as in starting, that the superheater has not been heated to the point at which the same is effective to superheat the steam. In such case, it may be desirable to supply saturated steam directly to the engine cylinders, as the saturated steam would then be of better quality than the steam passing through the superheater, owing to condensation in the superheater which tends to make the steam wet.

The principal object of my invention is to provide means by which either saturated or superheated steam may be supplied to the engine cylinders according to the desire of the engineer.

In the accompanying drawing, Figure 1 is a central sectional view of a selecting valve device embodying my invention, showing the parts in position for supplying saturated steam to the engine cylinders and Fig. 2 a similar view, showing the parts in position for supplying superheated steam to the cylinders.

The construction shown in the drawing comprises a casing 1 having a piston chamber containing a piston 2 and a cylindrical valve chamber containing a double piston valve having piston heads 3 and 4 carried by the valve stem 5, connected to piston 2. The chamber 6 formed by and intermediate the piston 2 and the piston head 4 is in open communication with a passage 7 leading to the pipe 8 which is connected to the usual locomotive steam throttle. The movement of the piston heads 3 and 4 controls communication to passages 9 and 10 connected respectively to pipe 11 from the superheater and pipe 12 leading to the engine cylinders. The piston 2 controls a passage 13 connected to pipe 14 leading to the superheater.

A manually operated plug cock 15 in the

casing 1 is provided with a port 16 adapted in one position to connect a passage 17 leading to saturated steam passage 7 with a passage 18 opening into chamber 19 at the right of piston 2 and in another position said port 16 is adapted to connect a passage 20 opening into chamber 19 with an atmospheric exhaust passage 21.

If it is desired to supply saturated steam to the engine cylinders, the cock 15 is turned to the position shown in Fig. 1, so that when the steam throttle is opened to start the locomotive, saturated steam is admitted to the pipe 8 and flows through passage 17, port 16, and passage 18 to chamber 19. The chamber at the left of piston head 3 is open to an atmospheric exhaust port 22, so that while saturated steam is also supplied to chamber 6 intermediate the piston 2 and piston head 4, the opposing pressures acting on the piston device are unbalanced and the steam pressure in chamber 19 operates to shift the piston device to the position shown in Fig. 1, in which the engine cylinder passage 10 is open to chamber 6, so that saturated steam is supplied directly to the engine cylinders. In this position the superheated steam passage 13 is closed by the piston 2, so that saturated steam is not supplied to the superheater and the same is therefore cut out of action.

If it is desired to use superheated steam, the cock 15 is turned to the position shown in Fig. 2, in which passage 20 is connected by port 16 with exhaust passage 21. The chamber 19 is thus vented to the atmosphere and when the steam throttle is opened saturated steam acting in chamber 6 exerts a differential pressure on the piston device, due to the area of the piston 2 being greater than the area of the piston head 4, and in a direction to cause the piston device to be shifted to the position shown in Fig. 2. In this position, the superheated steam passage 13 is open to chamber 6, so that saturated steam flows to the superheater and from the superheater the saturated steam flows through pipe 11 and passage 9 to the space intermediate the piston heads 3 and 4. The engine cylinder passage 10 being open in this position to the above space, superheated steam will be supplied to the engine cylinders instead of saturated steam.

A feed groove 23 may be provided in the

projection 24 through which passage 18 extends, so that when the piston 2 is seated on the face of said projection, free communication will be provided from passage 18 to chamber 19, thus insuring a sufficient supply of steam to the chamber for shifting the piston 2 to the left.

It will now be evident that with my improvement, the engineer may cause either 10 saturated or superheated steam to be supplied to the engine cylinders, according to the circumstances.

Having now described my invention, what I claim as new and desire to secure by Letters Patent, is:—

1. In a locomotive, the combination with engine steam cylinders, a source of saturated steam supply, a locomotive steam throttle, and a steam superheater, of a selecting valve device comprising a casing having a valve chamber and a piston chamber, piston valves in said valve chamber and passages controlled by said piston valves for supplying saturated steam to the 20 engine cylinders in one position and for supplying superheated steam from said superheater to the engine cylinders in another position, a piston connected to said piston 25 valves for supplying saturated steam to the engine cylinders in one position and for supplying superheated steam from said superheater to the engine cylinders in another position, a piston connected to said piston

valves, and a manually operated valve for supplying saturated steam to said piston for actuating the same.

2. In a locomotive, the combination with engine steam cylinders, a source of saturated steam supply, a locomotive steam throttle, and a steam superheater, a selecting valve device comprising a casing having a valve chamber and a piston chamber, piston valves in said valve chamber and passages controlled by said piston valves for supplying saturated steam from said source to the locomotive cylinders in one position and in another position superheated steam from the superheater to said cylinders, a piston of larger area than the piston valves for actuating said piston valves and subject on one side to saturated steam pressure, and a manually operated valve for controlling admission and release of saturated steam to and from the opposite side of said piston.

In testimony whereof I have hereunto set my hand.

WALTER V. TURNER.
